UNITED STATES PATENT OFFICE.

DEMETRY ISNOW, OF LOS ANGELES, CALIFORNIA, ASSIGNOR TO MICHAEL LESHING, OF LOS ANGELES, CALIFORNIA.

FILM-WINDING MACHINE.

1,382,288.

Specification of Letters Patent. Patented June 21, 1921.

Application filed June 10, 1918, Serial No. 239,319. Renewed November 29, 1920. Serial No. 427,209.

To all whom it may concern:

Be it known that I, DEMETRY ISNOW, a citizen of Russia, residing at Los Angeles, in the county of Los Angeles and State of California, have invented a new and useful Film-Winding Machine, of which the following is a specification.

My invention relates to the motion picture art and more particularly to the art 10 of developing and washing films. It is common practice in laboratories in which film is developed to wind the film on racks which are then placed in tanks in which they are developed and fixed.

15 My invention comprises means for winding the film evenly and at a uniform tension on such racks. The principal object of my invention is to provide a machine by 20 without the necessity of touching the film during the winding, and in such a manner that the film will be evenly distributed at a uniform tension across the rack.

Further objects and advantages will be 25 made evident hereinafter.

Referring to the drawings which are for illustrative purposes only.

Figure 1 is an end elevation of one embodiment of my invention.

30 Fig. 2 is a side elevation with the rack and supporting parts omitted.

Fig. 3 is an end view on an enlarged scale of the winding head.

Fig. 4 is a side view of the same.

35 Fig. 5 is a section on a plane represented by the line 5—5 of Fig. 3, this plane being viewed in the direction of the arrows.

Fig. 6 is a side elevation on a still further enlarged scale of a portion of the mechanism.

40 Fig. 7 is a view of a portion of the mechanism shown in Fig. 3 shown in a different position.

Fig. 8 shows method of securing inside 45 end of film.

In the form of my invention illustrated in these drawings, a base 11 is provided to which are secured rack supports 12, and head supports 13, these rack and head supports 50 being braced to the base 11 by members 14 for the purpose of making them rigid. Detachably mounted on a shaft 20 between the rack supports 12 is a rack 21, this rack

being driven by pulley 22 through a belt 23 which passes over idlers 24 to a similar 55 pulley 25 rigidly secured to a gear 26 which may be turned by a handle 27. The gear 26 also drives a pinion 29, which is rigidly secured to a head shaft 28, this head shaft being free to turn in bearings mounted in the 60 head supports 13.

Secured to the head supports are head guides 30 and 31, these guides being provided with V shaped grooves in which a head 32 slides. The head 32 consists of a top 65 frame guide 40 and a bottom frame guide 41 in which is rigidly secured a frame follower 42. A pin 43 is secured in the follower 42 and a compression spring 44 surrounds the pin 43 and presses against the 70 follower 42 and against a spring slide block 45 which is free to slide inside the guides 40 and 41 which are grooved as shown at 46 in Fig. 3.

Secured to the spring slide block 45 is 75 a fixed cam 47 through which the pin 43 passes, and co-acting with the fixed cam 47 and turning about the pin 43 is a movable cam 48 which is provided with an arm 49 connected through a pivoted link 50 with a 80 pair of arms 51. Also sliding between the guides 40 and 41 is a cam slide 52 through which the pin 43 passes, this cam slide having a friction brake 53 formed thereon. This friction brake engages a cone on a film 85 carrier 54 which is free to slide and turn on the pin 43 and which is held in engagement with friction brake 53 by means of a locking block 55 which is hinged at 56 to a block 57 which in turn is rigidly secured to the 90 guide 40. The end of the film is secured in a slot in the film carrier 54, as shown in Fig. 8. The locking block 55 is also secured, by means of a catch 60, to a block 61 secured to the guide 41. The screw 28 passes 95 through an opening in the guide 41 and is engaged by a nut 70, which is secured on arm 71, hinged at 72 on a block 73 secured to the guide 41.

The two arms 51 are located on either side 100 of the cam slide 52 and are each pivoted on a pin 80 which passes through the cam slide 52. A pin 81 serves to connect the link 50 to the arms 51 and extends over as shown at 54 and carries a roller 82 which is of a 105 proper size and shape to press against a

roll of film 90 placed on the film carrier 54. This roller 82 is pressed against the roll of film 90 by means of a tension spring 85.

The method of operation of my invention 5 is as follows:

The rack 21 being mounted as shown in Fig. 1, and the end 91 of the film 90 being secured to the rack, the handle 27 is rotated in such a manner as to move the film rack 10 in the direction of the arrow 92, the head 32 having been placed in such a position that the film 90 is led directly to one side of the rack 21. Further rotation of the handle 27 swings the rack 21 and winds the film thereon. During this winding the screw 28 moves the head 32 in the direction of the arrow 93 of Fig. 2, so that the film 90 is wound spirally on the rack. The friction brake 53 being forced over by the spring 44 tends to 15 put a tension on the film 90, so that it is uniformly wound on the rack 21. As the film is wound off the roll the diameter of the roll gets smaller, and if the friction on the friction brake 53 were constant, the tension 20 on the film would increase as the diameter of the roll decreases. It is, therefore, necessary to diminish the friction as the diameter of the roll of film 90 decreases, so that the tension on the film will remain constant. It is for this purpose that the cams 25 47 and 48 are provided. These cams have inclined surfaces, as shown in Fig. 6, so formed that as the cam 48 is rotated with relation to the cam 47, the distance between the block 45 and the cam slide 52 is varied. This movement of the cam 48 is controlled 30 by the movement of the roller 82, the parts moving from the position shown in Fig. 3 to the position shown in Fig. 7, as the diameter of the roll decreases. The parts are so proportioned that the distance between the members 45 and 52 is decreased as the diameter of the roll decreases, and the spring 44 is so constructed that this decrease relieves 35 sufficient tension on the spring 44 to decrease the friction between the members 53 and 54 in proportion to the decrease in diameter of the roll 90.

I claim as my invention:

50 1. A friction device for maintaining a uniform tension on a roll of material as it is unwound and therefore decreases in diameter comprising a carrier upon which the roll of material is carried; said carrier having a cone formed on one end thereof; a pin on which said carrier turns; a cam slide having a conical depression into which said cone fits; guides in which said cam slide is free to move along said pin; a spring slide block 55 through which said pin passes fixed to said guides; a fixed cam secured to said spring slide block about said pin; a movable cam free to turn on said pin, said movable cam coacting with said fixed cam to force said cam slide into engagement with said carrier; a roller; means by which the roller moves said movable cam; and a spring so placed as to hold said roller in contact with said material.

radial arm secured to said movable cam and by which said movable cam may be turned; a link pivoted at one end on said arm and at the other end on a roller pin; a roller turning on said pin and so situated as to bear on the outer surface of said roll of material; two members pivoted at one end on said roller pin and at the other end on a pivot fixed with relation to said guides; and a spring so placed as to hold said roller 70 in contact with said material.

2. A friction device for maintaining a uniform tension on a roll of material as it is unwound and therefore decreases in diameter comprising a carrier upon which the roll of material is carried, a pin on which said carrier turns; a cam slide free to move along said pin and thus exert frictional pressure on the end of said carrier; guides in which said cam slide is free to move along said pin; a spring slide block through which said pin passes fixed to said guides; a fixed cam secured to said spring slide block about said pin; a movable cam free to turn on said pin, said movable cam coacting with said fixed cam to force said cam slide into engagement with said carrier; a radial arm secured to said movable cam and by which said movable cam may be turned; a link pivoted at one end on said arm and at the other end on a roller pin; a roller turning on said pin and so situated as to bear on the outer surface of said roll of material; two members pivoted at one end on said roller pin and at the other end on a pivot fixed with relation to said guides; and a spring so placed as to hold said roller 75 in contact with said material.

3. A friction device for maintaining a uniform tension on a roll of material as it is unwound and therefore decreases in diameter comprising a carrier upon which the roll of material is carried; said carrier having a cone formed on one end thereof; a pin on which said carrier turns; a cam slide 80 having a conical depression into which said cone fits; guides in which said cam slide is free to move along said pin; a spring slide block through which said pin passes fixed to said guides; a fixed cam secured to said spring slide block about said pin; a movable cam free to turn on said pin; said movable cam coacting with said fixed cam to force said cam slide into engagement with said carrier; a roller; means by which the roller moves said movable cam; and a spring so placed as to hold said roller in contact with said material.

4. A friction device for maintaining a uniform tension on a roll of material as it is unwound and therefore decreases in diameter comprising a carrier upon which the roll of material is carried, a pin on which said carrier turns; a cam slide free to move 125 along said pin and thus exert frictional pressure on the end of said carrier; guides in which said cam slide is free to move along said pin; a fixed cam secured to said spring slide block about said pin; a movable cam free to turn on said pin; said movable cam coacting with said fixed cam to force said cam slide into engagement with said carrier; a roller; means by which the roller moves said movable cam; and a spring so placed as to hold said roller in contact with said material.

sure on the end of said carrier; guides in which said cam slide is free to move along said pin; a spring slide block through which said pin passes fixed to said guides; a fixed 5 cam secured to said spring slide block about said pin; a movable cam free to turn on said pin, said movable cam coacting with said fixed cam to force said cam slide into engagement with said carrier; a roller; means 10 by which the roller moves said movable cam; and a spring so placed as to hold said roller in contact with said material.

5. A friction device for maintaining a uniform tension on a roll of material as it is 15 unwound and therefore decreases in diameter comprising a carrier upon which the roll of material is carried, said carrier hav-

ing a cone formed on one end thereof; a pin on which said carrier turns; a cam slide having a conical depression into which said cone 20 fits; guides in which said cam slide is free to move along said pin; a spring slide block through which said pin passes; fixed to said guides; cam means for forcing said spring slide block against said carrier; a 25 roller contacting with the outer surface of said material; means by which the roller actuates said cam means, and a spring so placed as to hold said roller in contact with said material.

In testimony whereof, I have hereunto set my hand at Los Angeles, California, this 31st day of May, 1918.

DEMETY ISNOW.
